220,909

COMBINATION FISHING ROD SUPPORT AND BITE ALARM

George H. Jennings, 4821 N. La Sena,
Baldwin Park, Calif. 91706

Filed June 1, 1970, Ser. No. 23,230

Term of patent 14 years

Int. Cl. D22—08

U.S. Cl. D22—22

FIG. 1 is an elevational view of a combination fishing rod support and bite alarm, showing my new design;

FIG. 2 is a top view thereof;

FIG. 3 is a bottom view thereof;

FIG. 4 is an end view thereof; and

FIG. 5 is an end view showing the end opposite the end shown in FIG. 4.

I claim:

The ornamental design for a combination fishing rod support and bite alarm, as shown.
